UNITED STATES PATENT OFFICE

JOHN FLAHERTY, OF ST. LOUIS, MISSOURI

VENTILATING SYSTEM

Application filed June 28, 1930. Serial No. 464,438.

My invention has for its object to provide an improved ventilating system for small residences and buildings. The particular object of my invention is to impart to the air moving within the system a swirling upward movement which will assist the air to rise through the stack and to draw off gases and odors from within the building.

The invention may be contained in ventilating systems that vary in their details and, to illustrate a practical application of the invention, I have selected one form of construction as an example of the different embodiments of the invention and shall describe it hereinafter. The ventilating system chosen for purposes of illustration is shown in the accompanying drawing.

Fig. 1 illustrates diagrammatically a ventilating system installed in a small building. Fig. 2 illustrates a cross-section of the cap which covers the outside entrance pipe of the system. Fig. 3 is a side view of a ventilating head which is located within the building. Fig. 4 illustrates an end view of the ventilating head shown in Fig. 3. Fig. 5 illustrates the Venturi joint for receiving in the main stack the air drawn from the ventilating heads. Fig. 6 illustrates the valve for allowing the escape of condensed moisture in the system.

In the ventilating system shown for purposes of illustration, an outside pipe 1, having openings 3 and 4, is connected to the sewer line 2 at its lower end. The upper end is covered by a cap 6 which is formed to cause the air received into the pipe 1 to assume a swirling motion.

The cap 6 has a series of openings 7 which are arranged in staggered relation to each other. A pin wheel 10 is supported within the cap by a standard 11 and rotates about the standard 11 on a bearing member 12. It will be seen that the air received within the cap will be directed to assume a swirling motion preparatory to its movement through the ventilating system.

The pipe 1 is connected through its opening 3 to a Y-shaped pipe 15. The Y-shaped pipe 15 is connected with the stack pipe 20, which extends vertically through the interior

of the building to the roof. The stack pipe 20 is formed to increasingly graduate in cross-sectional area according to the movement of the inlet received by the stack pipe 20 at the different horizontal levels of reception 55 of the inlet pipes.

In order to connect a number of inlet pipes to the stack 20 and to give a directive stimulus to the air carried by the inlet pipes as it enters the stack, a venturi 25 is located in the stack 20. The stack 20 at this point changes in cross-sectional area, that is, the cross-sectional area of the stack pipe 20 below the venturi 25 is to the cross-sectional area of the stack above the venturi as 1 is to 2. The venturi 25 has a central chamber 26 having an opening 30 in the bottom, which is adapted to receive a section 21 of the stack pipe 20, and an opening 31 in its top adapted to receive a section 22 of the stack pipe 20. The section 21 of the stack pipe 20 extends well into the chamber 26 to a point just below the opening 31. As the air moves from section 21 through the venturi 25 and into section 22, there will be produced within the chamber 26 a slight vacuum which will tend to draw off the air within the chamber 26 and its connected pipes. 75

The venturi has a series of openings 27 which connect with the chamber 26. The openings 27 are adapted to receive the inlet pipes 28. The inlet pipes 28 carry the air and odors from several locations within the building to the venturi 25 and the stack pipe 20. The ends of the pipe 28 are connected with ventilating heads 40 which may be positioned within the building as desired. The ventilating heads 40 are cylindrical in shape, one end 41 having cut-out sections 42, and the other end being sealed. The head 40 may be provided with a supporting bracket 44 for locating the head on the wall of the building. A metal plate 43 is located over the end 41 of the head and has openings 45 which are located in alignment with the cut-out sections 42. The openings 45 may be formed by stamping and the cut portion 46 may be bent to form blades 47. The plate 43 is positioned and held by the bolt 49 so that the blades 47 will cause the air which 100

may pass through the openings 45 and the cut-out section 42 of the head to assume a swirling movement. This swirling movement will increase the tendency of the air to move through the head and the pipes 28 to the stack pipe 20 and upwardly to the top of the stack.

The top of the stack 20 may be protected as against the elements by a cap 50 having 10 openings 51 arranged in a staggered relation to each other. It will be seen that, throughout the system, it is desired to impart to the moving air a swirling motion and, consequently, the parts are arranged in order to 15 accentuate and direct the air into a circular motion in the same direction.

In order to allow for the drainage of water and moisture which may condense within the stack 20, a pipe 55 is connected to the Y-shaped pipe 15 and the opening 4 of the pipe 1. A spring valve 56 is located within the pipe 55 to prevent back draw of water through the pipe 55. The spring valve 56 is cone shaped and has a hollow ball 62 which 20 tends to cover the opening 57 in the small end of the valve. The ball 62 is supported on a shaft 59. The shaft 59 is slidably supported in a bracket 58 which extends across the large end of the valve.

30 In order to hold the hollow ball 62 against the opening 57, maintaining the valve closed and at the same time allow for escape of water, a spring 60 is located about the shaft 59. One end of the spring 60 abuts against the 35 bracket 58 and the other end against a nut or button 61 on the shaft 59 to spring press the ball 62 against the opening 57. The valve will allow the water to escape when the weight of the water is sufficient to overcome 40 the pressure of the spring and to move the ball outwardly. On the escape of the water, the spring 60 will return the ball to close the opening 57. The spring 60 may be adjusted by the nut 61 on the shaft 59.

45 I claim:

1. In a ventilating system for buildings, a stack located within the building and extending the height of the building, the stack formed to have a plurality of sections increasing in diameter, Venturi shells and tubes located intermediate the sections, a plurality of sets of ventilating heads, a plurality of sets of pipes interconnecting the heads to the shells, the said heads having a 50 diameter larger than the diameter of the pipes, the heads having baffle plates inclined to the axes of the heads to cause rotary movement of the air in the heads, the connecting pipes and the stack.

60 2. In a ventilating system having a stack, a Y-shaped pipe having a discharge outlet and an inlet connected to the lower end of the stack, the body of the Y-shaped pipe inclined to the horizontal and located in a vertical plane, one of the legs of the pipe con-

nected to the discharge outlet and inclined downwardly, a one-way valve located in the said leg for discharging the moisture of condensation within the stack and pipes, the other leg of the Y-shaped pipe inclined upwardly and connected to the air inlet.

In witness whereof I have hereunto signed my name to this specification.

JOHN FLAHERTY.
